[57] CLAIM

The ornamental design for tire or similar article, as
shown and described.

DESCRIPTION

FIG. 1 is a perspective view of a tire or similar article
showing my new design, it being understood that the
tread design is repeated throughout the circumference
of the tire, the opposite side being substantially the same
as that shown; and

FIG. 2 is a front elevation view showing only a
fragmentary portion of the tread design thereof for ease
of illustration with the remaining portion of the tire
being shown schematically by solid lines.
